UNITED STATES PATENT OFFICE.

EMIL JAGENBERG, OF DUSSELDORF, GERMANY.

LABELING-MACHINE.

1,143,968.

Specification of Letters Patent. Patented June 22, 1915.

Application filed August 7, 1914. Serial No. 855,540.

To all whom it may concern:

Be it known that I, EMIL JAGENBERG, a subject of the German Emperor, and residing at 107 Himmelgeisterstrasse, Dusseldorf, 5 Germany, manufacturer, have invented certain new and useful Improvements in Labeling-Machines, of which the following is a statement.

The present invention relates to labeling 10 machines, in which the labels are pulled by a roller off a reciprocating pile, the said roller having been previously provided with gum. This roller then delivers the label to a second roller, on which it lies with the 15 gummed side out and which rolls it onto the article to be labeled.

The present invention in particular relates to an advantageous construction of these rollers for pulling the labels from the 20 pile and delivering them to the articles to be labeled.

In the accompanying drawing Figure 1 is a vertical cross section through the machine. Fig. 2 is an end elevation of the machine. 25 Fig. 3 is a cross section through the rollers and the pile of labels. Fig. 4 is a part view of the rollers. Figs. 5, 6 are cross sections through the rollers according to Fig. 3, but in other operative positions.

30 Beneath the roller 2, which receives its gum from the roller 5 dipping into the gum vessel 4 and the gumming rollers 6, is arranged a slide 9 carrying the pile of labels 8 and slidably fitted on the rails 7. This 35 slide is reciprocated by means of a cam disk 20 fitted to shaft 30, against which cam disk bears a lever 21 on shaft 31.

To the shaft 31 are also fitted two levers 32, the free ends of which are coupled by 40 rods 33 with the slide 9.

The pile of labels 8 rests on a plate 34, which is carried by the rods 16, which are 45 slidably fitted in guides 35 on the slide 9.

The lower ends of the rods 16 carry cross 50 bars 16^a, to which springs 28 are attached. The other ends of which are secured to the guides 35. These springs thus tend to force the pile of labels upward against a rail 15, which lies across the pile, and which is secured 55 to the walls 36 connected to the slide 9. The rods 16 are toothed, and in these teeth engage pinions 11, on the shafts 11^a of which, journaled in the slide, ratchet wheels 10 are fitted. The latter are adapted 60 to be engaged by pawls 12^a formed on levers 12 which are fulcrumed to the slide. At the

left end of the slide run are arranged fixed stops 13, and at the right end of said run are arranged fixed stops 14^a having inwardly curved upper horns 14 as shown.

60 The roller 2 fitted to shaft 40 has a segment 41 which, on the roller revolving, receives the gum from the roller 6. At the front edge of this segment there are recesses 42, into which parts 43 engage, which are 65 adjustably fitted to arms 44. These arms are all clamped to a shaft 45 journaled in the roller 2, and on the one end of which, outside of the roller 2, a lever 46 is fitted, which carries a roller 47 and, at its end, a 70 set screw 48. The roller 47 bears against a cam disk 49 rigidly fitted to the body of the machine 1, as a spring 50 secured to the lever 46 and the roller 2 respectively tends to pull the lever inward. When the lever 49 has been turned as far inward as it will 75 go, the face ends of the parts 43 are at the same level with the surface of the segment (Fig. 3). The set-screw 48 then bears against a rigid stop 51 in the roller 2. In 80 arms 52 a roller 53 is suspended like a pendulum from the body of the machine 1, and bears against the roller 2, pressing the label against the segment, when the said roller 2 revolves. The label will, thus, be covered 85 all over with gum. Over the roller 2 a roller 54 is journaled on a shaft 55 in the body of the machine 1. The shafts 40 and 55 carry gears 3 of equal size, meshing with each other. Both rollers are therefore revolved 90 at the same speed but in opposite directions, the segment 41 and the segment 56 on the roller 54 rolling off on each other.

In front of the front edge of the segment 56 double-armed levers 58 are fitted loose on 95 a shaft 57 journaled in roller 54, said levers being arranged at the same pitch as the recesses in roller 2. To the radially projecting ends of these levers 58 are hinged arms 59 which carry at their one end thin 100 tongues 60, and at the other ends hold springs 61, secured to the arms 62, which are fitted to the hubs of the levers 58. The hubs of these levers 58 carry noses 63, against which the arms 59 are drawn by 105 means of the springs 61. The hubs of the levers 58 have, furthermore, slots 64, into which pins 65 engage, which are secured to shaft 57. The arms of lever 58, projecting inward are coupled by springs 66 with the 110 roller 54, namely with the block 67 serving as counterpoise to the segment 56. On the

one end of the shaft 57 is fitted a lever 68, which carries a roller 69, which is pulled by a spring 70 fitted to the lever and the roller respectively against a cam disk 71 fitted to the body of the machine.

Over the roller 54 is arranged a table 72, on which the articles to be labeled are piled. On this table is provided a slide 74 with a nose 75, which will, in known manner, push forward the lowermost of the articles 73 when the slide reciprocates. The slide 74 is coupled by means of rods 76 with levers 77, pivoted to the body of the machine and bearing with rollers 78 against two cam disks 79 of equal shape on the shaft 40.

When, as shown in Fig. 1, the pile 8 lies with its front edge directly under the front edge of the segment 41, the slide 9 will be moved to the right by the cam disk 20 at a speed which is equal to the circumferential velocity of the roller 2. As the pile 8 is at the same time pressed by the springs 28 upward and against the segment 41, the uppermost sheet of paper will adhere to the segment. Shortly before this travel of slide 9 is completed, the horns 14 on stops 14^a will engage the lower teeth of ratchet wheels 10, so as to turn the wheels, and thus lower table 34, by means of pinions 11 and racks 16. Directly after this operation has taken place stops 14^a will engage levers 12 of pawls 12^a, and thus force the pawls against the teeth of wheels 10, so that in this way the table is sustained in its lowered position.

The slide 9 now remains stationary until the sheet of paper has been completely pulled off the pile 8 and the segment 41 has passed it. Then the slide 9 with the pile is again moved to the left, and shortly before the end of this movement the levers 12 of pawls 12^a strike against fixed abutments 13, which swing the pawls off the teeth of the ratchet wheels, so that the racks 16 and the pile 8 will be raised by the springs 28 so far, that the pile is again pressed against the rail 15. Then the process repeats afresh.

The label hanging to the segment 41 is in the meanwhile pressed on tightly by the rotation of roller 2 and gummed all over. Shortly before the front edge of this segment has reached its highest position, the cam disk 49 rocks the lever 46 toward outside. Thereby the shaft 45 is turned in such a manner, that the parts 43 rock toward inside, and the recesses 42 are open (Fig. 4.) As soon as, now, the two front edges of the segments 41 and 56 touch each other, the cam disk 71 and the spring 70 cause the lever 68 to rock toward inside. Thereby the shaft 57 is turned in such a manner, that the springs 66 can pull the inner ends of the levers 58 toward inside. The tongues 60 will then also move from the position according to Fig. 3 into the position according to Fig. 5, so that they

enter into the recesses 42 and bear on the front edge of the label. The label is therefore now pressed with its front edge against the segment 56, so that, when the rollers 2 and 54 continue to revolve, it will be peeled off from the segment 41 and wrapped onto the segment 56 (Fig. 6.) When then the front edge of the segment has reached its highest position, the lowermost article is drawn by means of the slide 74 from the upper pile and pushed over the roller 54, so that the front edge of the label sticks to the article. Then the cam disk 71 causes the lever 68 to rock toward outside, whereby the shaft 57 is turned. The pins 65 therewith dog the levers 58 so that their arms extending radially toward outside are moved forward in the direction of the rotation of the roller 54. The tongues 60 are thus drawn out in a tangential direction between the article and the label, as the arms 59 move by such stroke of the levers 58 in such a manner, that the springs 61 are stretched (Fig. 6.) Now the roller 80 bearing on roller 54 and driven at the same circumferential velocity, but in an opposite direction to roller 54 presses the article tightly against the label and by its rotation pulls the article completely from the pile. By their further revolution the rollers 54 and 80 then roll the label together with the article between themselves, so that the former sticks to the latter. When the tongues 60 reach their highest position, the parts 43 having receded from the recesses 42 reach their lowest position and a fresh operation is commenced.

By the employment of the parts 43 it is obtained, that also those parts of the label, which come to lie on the recesses 42 for the entrance of the tongues 60, are gummed.

I claim:

1. Labeling machine comprising a slidable pile of labels, a rotary roller with a segment which receives gum and pulls off the uppermost label from the pile, recesses in the front edge of said segment, parts, adapted to be automatically engaged in these recesses and again withdrawn therefrom, a second roller, said roller carrying a segment, adapted to roll on the segment of the first roller, tongues on the second roller, means for rocking and pressing said tongues against the front edge of this segment, means for moving the articles to be labeled over the second roller, and for pressing said articles against the labels.

2. Labeling machine comprising a slidable pile of labels, a rotary roller with a segment which receives gum and pulls off the uppermost label from the pile, recesses in the front edge of said segment, parts, adapted to be automatically engaged in these recesses and again withdrawn therefrom, a second roller, said roller carrying

a segment, adapted to roll on the segment of the first roller, in said roller a shaft, on said shaft levers, linked to said shaft levers arms, attached to said arms tongues and springs, means for advancing the articles to be labeled and for pressing the said articles against the labels.

In testimony whereof I have hereunto set my signature in the presence of two witnesses.
